UNITED STATES PATENT OFFICE.

JOSEPH DICK, OF CANTON, OHIO.

FODDER-CUTTER.

SPECIFICATION forming part of Letters Patent No. 683,448, dated October 1, 1901.

Application filed July 10, 1899. Serial No. 723,319. (No model.)

To all whom it may concern:

Be it known that I, JOSEPH DICK, a citizen of the United States, residing at Canton, in the county of Stark and State of Ohio, have 5 invented new and useful Improvements in Fodder-Cutters, of which the following is a specification.

My invention relates to improvements in 10 fodder cutters or shredders; and it has for its object the casting of the supporting-frame and fan-casing in one and the same piece, and other features and details of construction, as will be hereinafter more fully described and claimed.

15 Figure 1 is a perspective view of the rear of the machine viewed from the right-hand side thereof. Fig. 2 is a perspective view of the rear of the machine viewed from the left-hand side thereof. Fig. 3 is a vertical sectional view through the center of the machine. Fig. 4 is a perspective view of the front of the machine and from the right-hand side thereof. Fig. 5 is a detailed view of the eccentric locking-pin. Fig. 6 is a cross-sectional view of a portion of the frame, showing the means for closing the openings therein. Fig. 7 is a perspective view of a portion of the frame, showing the lugs through which are passed the eccentric locking pins or bars. 25 Fig. 8 is a perspective view of one of the doors or openings in the frame in the rear of the machine for the removing of obstructions. Fig. 9 is an end view of the locking-block adapted to be engaged to the shaft of the gear-shifting mechanism. Fig. 10 is a detailed perspective view showing the engagement of the locking-block with the shaft and spring. Fig. 11 is a perspective view of the shear-plate. Fig. 12 is a plan view of the end 30 of the shear-plate and its engagement with the frame. Fig. 13 is a plan view of the left-hand side of the shear-plate and its engagement with the frame. Fig. 14 is a perspective view of a section of the frame with which is engaged the right-hand end of the shear-plate. Fig. 15 is a detailed perspective view of the shear-plate. Fig. 16 is a detailed perspective view of the key-bolt by means of which the shear-plate is held in engagement 35 with the frame. Fig. 17 is a sectional view through the lower feed-roller, shear-plate, and a portion of the frame, illustrating the

relation of said parts to each other. Fig. 18 is a detailed perspective view of the end of the shaft which drives the upper feed-roller. 55 Fig. 19 is a detailed perspective view of the box and the method of engagement with the shaft and the upper feed-roller. Fig. 20 is a detailed perspective view of the left-hand end of the upper feed-roller. Fig. 21 is a longitudinal sectional view of the box and end of the upper feed-roller. Fig. 22 is a detailed view of a portion of the frame, showing the boxes in which are carried the upper and lower feed-rollers. Fig. 23 is a plan view of 60 the gear-shifting mechanism by which the feed-rollers are driven. Fig. 24 is a detailed perspective view of a section of the box and sleeve which carries the rear end of the main driving-shaft. Fig. 25 is a sectional view of 70 the rear box and its engagement with the frame. Fig. 26 is a sectional view of the forward or adjustable box and its engagement with the frame. Fig. 27 is a detailed perspective view of the rocking shaft by means 75 of which the clean-out to the fan-casing is operated. Fig. 28 is a detailed perspective view of a portion of the fan-casing, showing the means of engaging the detachable sectional plates therewith. Fig. 29 is a detailed perspective view of one of the sectional plates. Fig. 30 is a detailed perspective view of the locking-bar. Fig. 31 is a detailed perspective view of the spout or exit of the fan-casing. Fig. 32 is a side elevation of the fan-casing, showing the feed-box, feed-rollers, and some of the coöperating parts in vertical 80 longitudinal section. Fig. 33 is a vertical cross-section on a line centrally through the feed-box and rolls and adjacent parts. 85

In the accompanying drawings similar letters of reference refer to similar parts.

A represents the fan-casing and supporting-frame, which is cast in a single piece and provided with the extension-lugs a and a' , 95 adapted to engage the wooden supporting-frame B, which may be of any desired form of construction. The fan-casing A is shown and I prefer to construct it in circular form, with the reinforcing-ribs a^2 and a^3 on the rear of the casing and a^4 , a^5 , a^6 , and a^7 on the front of the casing. I also provide on the front of the casing the substantially semicircular strengthening-rib a^8 at the edge of the air- 100

inlet and upon the rear of the casing the strengthening-rib a^9 around the edge of the air-inlet. Upon the front and rear at the center of the casing there are provided supports a^{10} and a^{11} for the journal-boxes, which carry the main driving-shaft. For the purpose of adjustment or of removing obstructions upon or about the cutters or shredders I have provided openings C and C' in the casing and upon either side thereof projecting lugs c and c' . A plate c^2 conforming to each of the openings and having projecting flanges is provided. To hold these plates in position upon the casing, an eccentric bar c^3 is provided, which passes through openings in the lugs c and c' and when turned up holds the plate in engagement with the casing. For the purpose of relieving any clogging in the casing in case of stoppage in the discharge-pipe I have provided at the bottom of the casing an opening or aperture D, over which there is placed a hinged door d. A rocking shaft d' is journaled in the wooden supporting-frame, and mounted thereon is a toggle-joint d^2 , which has a pivoted connection with the door d. For the purpose of operating the rocking shaft there is mounted thereon a lever d^3 , which has a linked connection by means of a rod d^4 with the elbow-lever d^5 , journaled upon the feed-box of the machine. To enable the elevation of the discharge-pipe to be changed as may be desired, I have provided the casing with projecting flanges a^{12} and a^{13} and segmental plates a^{14} , a^{15} , and a^{16} , one of which has cast integral therewith the opening or spout connection for the discharge-pipe. These plates are so formed as to extend over and engage with the flanges a^{12} and a^{13} and are held in position by means of the straps a^{17} , which are bolted to the segmental plates and the flanges on the fan-casing. When it is desired to change the elevation of the exit or discharge pipe, one of the segmental plates may be removed and the plate carrying the discharge-exit may be raised or lowered, when the segmental plate may be placed in the position formerly occupied by a portion of the discharge-segment and securely locked in position.

Mounted in the center of the fan-casing and upon journal-boxes, that will be herein-after more fully described, there is a driving-shaft E, carrying the fly-wheel F, to which there may be attached any desired form of cutter or shredder and the fan-flights. The rear journal-box G, in which is journaled the end of the shaft E, consists of two pieces g and g' , adapted to be bolted together and having upon their forward end a sleeve g^2 , provided with a spiral rib g^3 , formed on the inside of said sleeve. This sleeve g^2 passes over the hub of the fly-wheel F, upon which there are cast ribs f' , the result being that the ribs f' upon the hub of the fly-wheel carrying any portion of the fodder which may have fallen upon the hub around the same when coming in contact with the spiral rib

g^3 on the inside of the sleeve it is conducted off of and turned away from the hub. The box H, in which is journaled the forward end 70 of the shaft E, consists of two pieces h and h' , which are supported in the projecting flange a^{11} , formed on the casing or supporting-frame. On the lower side of the lower half of the box there are projecting lugs h^2 75 and h^3 , which engage with a screw-threaded bolt h^4 , which has a screw-threaded engagement with the projecting lug a^{11} , and upon this screw-threaded bolt there is formed a bolt-head h^5 . Upon the top of the projecting 80 supporting-lug a^{11} there are bolted collars a^{18} , which project over the edge of the sliding box H and hold it against vertical displacement. This sliding box H abuts against the outer hub of the fly-wheel F, and in case 85 there should be any change in the relative position of the fly-wheel and the cutting edge or plate, which is apt to be the case, due to the rapid revolution of the fly-wheel, the same can be readjusted without stopping the machine by means of turning the bolt-head h^5 , which carries with it the sliding box H. It is very important in this class of machine that the relation of the cutters or shredders to the cutting edge or bar be capable of adjustment 95 without stopping the machine, and I have provided the mechanism thus described for that purpose.

On the forward end of the driving-shaft E there is provided the usual driving-pulley e, 100 which may be attached to the shaft in any desired manner, either by key or by the usual thumb-bolt. Upon the rear end of said driving-shaft E there is mounted a gear-wheel e' , 105 which engages with and drives the gear train I, by means of which the feed-rollers are operated. To the rear end of the casing there is securely bolted the feed-box J, the forward end of which carries the journal-boxes j and j' upon either side thereof, in which is 110 journaled the lower feed-roller. There are also provided the vertically-slotted apertures j^3 and j^4 , which receive the sliding boxes carrying the upper feed-roller. At the left-hand side of the feed-box, journaled in brackets securely bolted thereto, there is mounted the shaft i, carrying the bevel-gears i' and i^2 115 and the shifting sleeve i^3 , having therein a slotted aperture i^4 , which engages a pin i^5 upon the shaft. Said shifting sleeve is also 120 provided with circumferential ribs i^6 and i^7 , which engage with a shifting arm i^8 , which is securely bolted to the shifting rod i^9 , supported in brackets attached to the journal-boxes of the shaft i. The shifting sleeve is provided 125 at both ends with the usual form of projecting clutch lugs or jaws adapted to engage corresponding jaws of the bevel-gears. For the purpose of shifting the sleeve I have provided an eccentric locking-lever K, which is connected to the shifting bar i^8 by means of a link k. The eccentric locking-lever K is mounted upon a square shaft which extends across and below the rear of the feed-box and has securely 130

attached to its outer end a locking-block k' , which engages with a spring k^2 , bolted to the feed-box. In operation the shifting lever K being thrown forward, the link k carries forward the shifting rod i^9 , which in turn carries forward the shifting sleeve. When it is desired to reverse the movement, the shifting lever is thrown backward, and the operation is reversed, and the parts are held in engagement by means of the engagement of the locking-block k' with the spring k^2 , the operation in each movement being to throw the eccentric-lever past the center, where it is more readily held in the desired position. In brackets 15 ets securely bolted to the under part of the feed-box there is journaled the shaft i^{11} , carrying the bevel gear-wheel i^{10} upon one end and the chain sprocket-wheel i^{12} upon the other, which by means of the chain i^{13} drives 20 the chain-wheel i^{14} , mounted upon the hub of the lower feed-roller. There is also attached to the journal-box supporting the lower feed-roller by means of the bracket i^{15} the ordinary form of chain-tightener i^{16} . 25 The lower feed-roller L is cylindrical in form and may be provided with either a smooth or corrugated surface. I have shown it, however, provided with a corrugated surface. The right-hand end thereof is open or re- 30 ceased, and the coupling l for the driving-shaft is provided with a longitudinal slot l^1 , formed in a hub cast in the interior of the cylindrical feed-roller, which engages a pin l^2 , set into the end of the shaft l^3 . There is 35 also provided in the journal-box j a corresponding longitudinal slot which permits of the passage of the pin and shaft through the journal-box. By this construction the coupling is self-contained, thus utilizing all the 40 width of the feed-box and preventing the clogging or obstructing of the roller by reason of the close abutment of the end of the roller against the inner face of the feed-box, thus completely covering the inward projection of 45 the bearing and the inwardly-projecting annular flange formed around said bearing. On the other end of the shaft l^3 there is provided a gear-wheel l^4 for the purpose of driving the upper feed-roller, the end of the shaft l^3 being 50 journaled in a casing or frame securely bolted to the fan-casing. The upper feed-roller M is also cylindrical in form and may be either smooth or corrugated; but I have shown it corrugated. On either end are pro- 55 jecting flanges m and m' , which abut against the supporting-frame upon either side. The roller is made hollow and has a universal-joint connection with the driving-shaft, and is thus enabled to rise vertically in the slot- 60 ed frame upon either side. The driving-shaft m^3 is journaled at its left-hand end in a box having an oscillating connection with a bracket or casing bolted to the fan-casing and carries a gear-wheel m^4 , the cogs 65 of which are slightly beveled on one side. The other end of the driving-shaft m^3 is provided with a pin m^5 for engagement with

a coupling device m^6 , which is carried by the sliding journal-box m^7 , mounted in the vertical aperture heretofore described. The coupling device m^6 consists of a hollow casting, the opening therein corresponding to and receiving the end of the shaft and having cast thereon lugs m^8 and m^9 about slotted apertures to receive the pin m^5 upon the end of the shaft. Upon the other end of the coupling device there is cast a ball provided with substantially V-shaped communicating openings m^{10} and m^{11} , said ball being adapted to be passed into the upper feed-roller when a pin m^{12} is driven through openings m^{13} and m^{14} in the feed-roller and through the openings in the ball, thus coupling the feed-roller with the driving-shaft. By this mechanism the feed-roller is enabled to rise and fall, adapting itself to the quantity of material fed to the machine.

The cutting edge or bar N consists of a single piece of metal having a straight cutting edge next to the knives and a corrugated edge next to the feed-roller and at either end is provided with beveled projecting lugs n and n' for engagement with corresponding recesses in the fan-casing. The recess O in the fan-casing on the right-hand side, adapted to receive the beveled projecting lug on the cutting edge or plate, is provided with a vertical wall o and a slightly-beveled wall o' , against which abuts the corresponding sides of the flange upon the cutting edge or bar N. On the left-hand side of the casing I provide a recess P, which has a projecting flange p and a key-bolt p' , having a slightly-beveled side p^2 , which when the key is passed up through the aperture p^3 , provided therefor in the fan-casing, engages the corresponding beveled edge on the cutting edge or plate and locks it in engagement with the fan-casing. By this novel mechanism the cutting edge or plate can be readily removed to repair any damage which may occur thereto and if it should become broken or damaged would not necessitate any repair to the fan-casing. On the lower edge of the cutting edge or plate there is provided an apron n^2 , the lower edge of which engages with the outer edge of the opening of the fan-casing, so that in case any damage should occur to the cutting edge or plate it would fall outside of the casing, and thus become disengaged from the machinery.

In operation, the driving-belt having been applied to pulley e , the shaft E is caused to revolve, carrying with it the fly-wheel F, upon which are mounted the cutters and fan-flights. The motion is thus transmitted through the gear-wheel mounted on the end of the shaft to the gear-shifting device heretofore described and by means of the chain and sprocket-wheel to the lower feed-roller and by it in turn to the upper feed-roller. The material to be cut being fed into the feed-box, the upper feed-roller readily adapts itself thereto, and the material is carried through the feed-rollers over the cutting-

plate and engages with the cutters mounted upon the fly-wheel and falls to the lower portion of the fan-casing, where by reason of the current generated by the revolution of the fan-flights it is taken up and carried out through the spout or conveyer to the point of deposit. In case the material should be fed into the machine more rapidly than it could be conveyed out of it by the means provided and to avoid clogging the vent at the lower part of the fan-casing can be opened by the operation of the eccentric lever and the rocking shaft described when a portion of the material is discharged from the casing.

In event it should be desired to remove any obstructions which may have adhered either to the fan-flights or to the cutting-knives the gates or doors provided at the top or upon either side of the fan-casing can be readily opened and replaced. If it should be desired to change the elevation of the discharge-pipe, one or more of the segmental plates on the fan-casing may be detached, the spout raised or lowered, and the segmental plates again replaced at the points vacated by the changing of the position of the spout without interfering in any way with the balance of the machine. As heretofore referred to, in the operation of this class of machines, which require very rapid revolution of the fly-wheel carrying the knives, the relation of the knives to the cutting edge or bar changes as the speed increases. To avoid this difficulty, I have provided the adjustable sliding box H, heretofore described, which enables the operator to adjust the cutting-knives to the cutting edge or bar while the machine is in operation.

Having thus fully described my invention, what I desire to secure and claim is—

1. The combination in a fodder-cutter, of a fan-casing and supporting-frame comprising an annular rim and sides formed of a single piece of material, said casing being provided in each side with an air-inlet, in its rim with a detachable discharge-segment, and upon the base portions of the walls of said air-inlets with integral bearing-supports, journal-boxes detachably mounted on said supports, a drive-shaft journaled in said boxes, and carrying the cutting-knives and fan-flights, a cutting-bar inclosed with the shaft, knives and fan-flights in said casing, and feed mechanism, substantially as described.
2. In a fodder-cutter, a combined casing and supporting-frame formed of a single piece of material and comprising an annular rim and sides, said rim being provided with a detachable discharge-segment and the sides with air-inlet openings, and integral journal-bearing supports at the base portions of the walls of the openings, substantially as set forth.
3. In a fodder-cutter, and as a new and improved article of manufacture, a combined cylindrical casing and supporting-frame comprising vertical circular sides and an annular connected rim formed of a single piece of ma-

terial, said rim being provided with one or more openings and the sides with air-inlets at the base of each of which is formed a journal-bearing support, substantially as described. 70

4. In a fodder-cutter, a combined casing and supporting-frame provided with one or more openings in its rim and in its sides with 75 always open air-inlets at the base of each of which is formed a journal-bearing support, substantially as described.

5. In a fodder-cutter, a combined casing and supporting-frame provided in its sides 80 with always open air-inlets, at the base of which is formed a journal-bearing support, and in its rim with openings, combined with a series of detachable interchangeable segments for closing said openings, and a discharge-pipe carried by one of said segments, substantially as set forth. 85

6. The combination in a fodder-cutter, of a supporting-frame, with a sliding journal-box mounted therein, and provided with depending lugs, and a screw-threaded bolt having a screw-threaded engagement with the supporting-frame, the ends thereof abutting against the depending lugs of the sliding box, substantially as described and for the purpose 95 set forth.

7. The combination in a fodder-cutter, of a supporting-frame with a journal-box having a projecting sleeve provided on its inner end, with a conical spiral rib, a main driving-shaft 100 journaled therein, and a fly-wheel mounted thereon having a projecting ribbed hub extending into said journal-box, substantially as described and for the purpose set forth. 105

8. The combination in a fodder-cutter, of a supporting-frame having journaled therein a driving-shaft carrying a fly-wheel having cutters mounted thereon, with a feed-box having journaled therein an upper and lower feed-roller, means for communicating power from the driving-shaft to the lower feed-roller, and thence to the driving-shaft of the upper feed-roller, a flexible coupling between said driving-shaft and the upper feed-roller, consisting of a hollow casting, the opening therein 110 at one end corresponding to and receiving the end of the shaft, and having a slotted aperture therein to receive a pin mounted upon the driving-shaft, the other end thereof being globular in form and provided with reversed- 115 V-shaped communicating openings to engage a pin to be passed through the end of the upper feed-roller and said openings, substantially as described and for the purpose set forth. 120

9. A flexible coupling device for feed-rollers for fodder-cutters, consisting of a hollow casting, the opening therein at one end corresponding to and receiving the end of the shaft, and having a slotted aperture therein to receive a pin mounted upon the driving-shaft, the other end thereof being globular in form and provided with reversed- 125 V-shaped communicating openings to engage a pin passed 130

through the end of the upper feed-roller and said openings, substantially as described and for the purpose set forth.

10. The combination in a fodder-cutter, of 5 a supporting-frame carrying a driving-shaft having mounted thereon a fly-wheel provided with cutters, with a feed-box having journaled therein the upper and lower feed-rollers, and means for communicating the motion of the driving-shaft to the lower feed-roller, an open-ended cylindrical lower feed-roller, and a driving-shaft connected thereto by means of a pin on the end of the shaft, engaging a longitudinal slot in a hub cast in 15 the interior of the cylindrical feed-roller, substantially as described and for the purpose set forth.

11. In a fodder-cutter, a casing provided with a rim having a series of detachable interchangeable segments, and a discharge-pipe carried by one of said segments, substantially as set forth.

12. In a fodder-cutter, a casing provided with a rim having an opening and formed at 25 opposite sides thereof with flanges, a series of interchangeable segmental plates for closing said opening and adapted to engage said flanges, one of said plates carrying a discharge-pipe, and fastenings for securing the 30 plates to the flanges, substantially as set forth.

13. In a fodder-cutter, the combination of a supporting frame or casing, a driving-shaft mounted therein and carrying a fly-wheel provided with cutters, a feed-box connected 35 to the casing, feed-rollers mounted in the box, and a shear-plate mounted in the frame and projecting into the feed-box and having a depending apron, the lower edge of which engages the outer surface of the frame or casing, whereby, in the event that any damage 40 should occur to the cutting edge, or plate, it would fall outside the casing, and thus become disengaged from the machinery, substantially as described.

45 14. The combination in a fan-casing for fodder-cutters, of clean-out apertures with projecting lugs on both sides thereof, covering-plates provided with projecting flanges, and an elastic eccentric locking-bar adapted 50 to engage the projecting lug and covering-plates, substantially as described and for the purpose set forth.

15. In a fodder-cutter, the combination of a driving-shaft carrying the cutting-knives and 55 fan-flights, the feed-rollers, a second shaft in gear with the feed-rollers and carrying a bevel gear-wheel, a third shaft in gear with said driving-shaft and carrying loose bevel-pinions each provided with a clutch member and 60 meshing with said bevel gear-wheel on the

second shaft, a sliding sleeve on the third shaft, a pin upon the third shaft engaging a slot in the sliding sleeve, clutch members upon the ends of the sliding sleeve to engage the clutch members on the bevel-pinions, a 65 sliding shaft mounted parallel with the third shaft, a shifting lever engaging the sleeve and driving-shaft, and an operating and locking lever having a linked connection with the driving-shaft, substantially as described. 70

16. In a fodder-cutter, the combination of a casing provided with a feed-opening the walls of which are provided on opposite sides of the opening with beveled recesses O and P, the recess O having a vertical wall o and a beveled wall o' and the recess P a projecting flange p having an aperture p³ a key-bolt p' fitted in said aperture and having a beveled side p², a drive-shaft mounted in the casing, and a carry fly-wheel provided with cutters, 80 a feed-box connected to the casing, feed-rollers therein, and a shear-plate provided with beveled projecting lugs coöperating with said recesses O and P and the bolt p', and having a depending apron, the lower edge of which 85 engages the outer surface of the casing, substantially as set forth.

17. In a fodder-cutter, the combination, with a fan-shaft, of a drive-shaft operated thereby, feed-rollers, a second shaft for operating said rollers and carrying a gear, a pair of gears loosely mounted on the drive-shaft and meshing with the gear on the feed-roller shaft, a shifting clutch-sleeve adapted to engage either one of the drive-shaft gears to 90 rigidly connect it to said shaft, an eccentric for operating the clutch-sleeve, and a cam-locking block coöperating with said lever, 95 substantially as set forth.

18. In a fodder-cutter, the combination 100 with the fan-casing, of the fan-shaft, a feed-box connected to the casing, feed-rollers, a drive-shaft, a feed-roller shaft for operating said feed-rollers, a train of gearing connecting the drive and feed-roller shafts, gear-shifting mechanism coöperating therewith, 105 an eccentric lever for operating the gear-shifting mechanism, a locking-spring on the feed-box, a shaft connected at one end to said lever, and a cam-locking block on the opposite end of the shaft and bearing against said spring, substantially as set forth.

In testimony whereof I have hereunto set my hand in the presence of two subscribing witnesses.

JOSEPH DICK.
